DRY SHAVER

James Henry Rand, Jr., Stamford, Conn., assignor, by mesne assignments, to Remington Rand Inc., Buffalo, N. Y., a corporation of Delaware

Application May 28, 1938, Serial No. 210,684

5 Claims. (Cl. 30—43)

This invention relates to improvements in the shearing head for razors of the dry shaver type, and more particularly to the construction of the cutting members therefor.

The shearing head of the invention is used with a razor similar to that disclosed and described in the patent application of H. Landsiedel, S. N. 123,162, filed January 30, 1937, patented October 25, 1938, and No. 2,134,134.

Most of the razors now in use are ineffective for use in cutting long hair. This is due to the fact that no adequate combing device is provided for collecting the air into contact with the shearing edge.

It is, therefore, the principal object of this invention to provide a shearing head in which adequate combing facilities are provided for combing long hair into the cutter.

Another object is to provide a shearing head having two separate and distinct areas, one for shaving, and the other for cutting long hair.

A more clear conception of the construction, operation, and further objects of the invention may be had from the following specification when read in conjunction with the accompanying drawing, in which

Fig. 1 is a side elevation of the upper portion of a dry shaver, having parts thereof broken away to show the operating mechanism of the inner cutter;

Fig. 2 is an enlarged cross section of Fig. 1 taken along line 2—2 thereof;

Fig. 3 is a cross section through 3—3 of Fig. 2;

Fig. 4 is a cross section through 4—4 of Fig. 2;

Fig. 5 is a plan view of the outer cutter;

Fig. 6 is a side elevation of the inner cutter;

Fig. 7 is a schematic showing of a hair in position to be cut.

Figs. 1 and 2 disclose a casing or handle 10 similar to that described in the above patent application. Through openings 11 and 12 in casing 10, extend resilient plungers 13 and rock lever 14, respectively. Removably affixed to the casing 10 by a set screw 15 is the shearing head 16, which comprises a fixed outer cutter 17 and an inner cutter 18. Openings 19 and 20 in the base of the shearing head 16 correspond with the openings 11 and 12 in casing 10, and are provided for plungers 13 and rock lever 14, respectively. The rock lever 14 is oscillated by any well known type of motor (not shown).

The outer cutter member 17 has a curved shaving section forming the outer portion thereof. A central circular bore is formed in the outer cutter as shown in Fig. 2. The outer surface of

outer cutter 17 has its upper arcuate surface ground away in the center to form three flat surfaces 21, 22, and 23, disposed at obtuse angles to each other. The metal at the edges of the cutter is left to form ribs or ridges 24, which are adapted to protect the razor and to form a means for stretching the skin when the cutter is applied to the face. Slots 25 are cut through the flat surfaces 22 and 23 into the central bore, said slots extending from the surface 21 down the side of the cutter. These slots leave a plurality of comb or cutter bars, the inner edges of which constitute shearing edges. The metal remaining under the surface 21 forms a web or longitudinal bar, which tends to strengthen and maintain the cutter rigid. This web or longitudinal bar is located at one side of the medial plane of the cutter.

Cut in the bars in face 23 is a longitudinal slot 26 which extends into the bore at an angle as shown in Fig. 2. This slot divides the bars into two separate sets, the upper set forming a comb with blunt cutting teeth 27.

The inner cutter 18 is substantially cylindrical in form, and has an eccentric bore. Cut in the portion of the cutter having the thickest wall is a slot 28, which is adapted to be engaged by the lever 14. Cut in and extending through the wall diametrically opposite to slot 28 is a plurality of transverse slots 29 leaving a plurality of cutter bars 29', the edges of which constitute shearing members. The inner cutter member is formed with longitudinally extending channels 29" at opposite ends of cutter bars 29' to form shoulders 29' at opposite ends of cutter bars 29', to relieve the friction between the inner and outer cutters, and to insure that the shearing edges will be in close engagement with the inner surface of the outer cutter. It will be noted that channels 29 on the side adjacent the slot 26 are arranged so that the shoulders at the ends of cutter bars 29' are intermediate the ends of the blunt teeth 27, thereby obviating the possibility of cutting the skin which might be drawn in by the comb.

The side of the shaver head provided with the flat surface 23 is formed with a plurality of complementary bars 29b at the outer side of the shaving section by the slotting operation that provides slots 25. Bars 29b project upwardly and toward the ends of blunt cutting teeth 27 but terminate in spaced relation relative thereto in order to form slot 26. The formation of longitudinal channels 29" in inner cutter member 18 at opposite ends of cutter bars 29' provides flat faces 29c. These flat faces 29c are on the outer

face of inner cutter 18 and extend from the bottom portions of shoulders 29^a in the manner illustrated in Fig. 2 to provide a space between the inner and outer cutters under the portion of the shaving section at the outer ends of the blunt cutting teeth 27, complementary bars 28^b and the outer ends of the cutter bars formed by the slotting of the shaving section throughout the portion provided with flat face 22. This allows the hair entering the slots between the bars of the outer shaver head to bend into the inner bore therein ready to be immediately cut off as soon as the hair extends into slots 29 between the ends of cutter bars 29'.

In operation the inner cutter is reciprocated by the lever 14, thereby moving the shearing edges of the inner cutter across the edges of the outer cutter. If the surface 22 is brought into engagement with and moved over the face in a direction parallel to the slots 25, short hair will be combed into the slots 25 and 29, and sheared off by the action of the cutters.

If it is desired to cut long hair, the surface 23 is brought into engagement with the skin, and the hair is combed by the teeth 27 into the position shown in Fig. 7. As will be seen, the hair 30 lies in the slot 25 and is looped into the slot 29. As the inner cutter oscillates the next adjacent shear edge cuts the hair.

While I have described what I consider to be a highly desirable embodiment of my invention, it is obvious that many changes in form could be made without departing from the spirit of my invention, and I, therefore, do not limit myself to the exact form herein shown and described, nor to anything less than the whole of my invention as hereinbefore set forth, and as herein-after claimed.

What I claim as new, and desire to secure by Letters Patent, is:

1. A dry shaving head comprising an outer cutter member having a curved shaving section, said section having U-shaped ribs at opposite ends, a longitudinal bar joining the central portions of said ribs, a plurality of spaced parallel cutter bars having opposite ends integral with said longitudinal bar and one side of said section, a plurality of blunt cutting teeth projecting laterally in spaced parallel relation from the opposite side of said longitudinal bar, complementary bars on the other side of said section projecting in aligned relation toward the ends of said teeth and terminating in spaced relation to said teeth, the outer surface of the first-mentioned bars lying in a plane in substantially perpendicular relation to the plane of the outer surfaces of said blunt teeth and complementary bars, each of said planes being in inclined relation to the sides of said cutter member, said bars and teeth having continuous partially cylindrical inner surfaces defining a bore in said cutter member, and an inner cutter member having a plurality of spaced parallel cutter bars formed with a partially cylindrical outer surface complementary to the partially cylindrical inner surface of the bars and teeth of said outer cutter member for cutting cooperation between said bars during the reciprocation of one of said cutter members relative to the other, said cutter bars of said inner cutter member having opposite ends terminating intermediate the ends of said first-mentioned cutter bars and said teeth, respectively, said inner cutter member being formed to provide shoulders at the ends of the cutter bars thereon in substantially perpendicular relation to said teeth and first-

mentioned cutter bars and said inner cutter member having longitudinally extending channels on each side thereof under the outer ends of said first-mentioned cutter bars and said complementary bars, and adjacent to said shoulders.

2. A dry shaving head comprising an outer cutter member having a curved shaving section, a longitudinal bar forming the central portion of said section, a plurality of spaced parallel cutter bars having opposite ends integral with said longitudinal bar and one side of said section, a plurality of blunt cutting teeth projecting laterally in spaced parallel relation from the opposite side of said longitudinal bar, the other side of said section being formed to provide an opening at the ends of said teeth, said cutter bars having flat outer surfaces lying in the same plane, said blunt teeth having flat outer surfaces lying in a common plane substantially perpendicular to the plane of said cutter bars, said teeth, longitudinal bar and cutter bars having an inner surface forming a partially cylindrical longitudinal bore in said outer cutter member, and an inner cutter member formed to provide a partially cylindrical section having bearing engagement with the partially cylindrical inner surface of said outer cutter member under said longitudinal bar and the adjacent portions of said first-mentioned cutter bars and said teeth but terminating inwardly of the ends of said teeth and intermediate the ends of said first-mentioned bars, and said inner cutter member being formed to provide longitudinally extending channels under the outer ends of said teeth and first-mentioned bars at the ends of the cutter bars thereon.

3. A dry shaving head comprising an outer cutter member having a curved shaving section, a longitudinal bar forming the central portion of said section, a plurality of blunt cutting teeth projecting laterally in spaced parallel relation from one side of said longitudinal bar toward one side of said section, a plurality of complementary bars on said one side of said section projecting in spaced parallel relation toward said blunt teeth in aligned relation therewith and terminating in spaced relation relative thereto, said cutter member being formed with a longitudinal bore providing partially cylindrical surfaces at the inner edges of said bars and teeth, and an inner cutter member having a plurality of spaced parallel cutter bars formed with a partially cylindrical outer surface complementary to the partially cylindrical inner surface of the bars and teeth and engaging said inner surface throughout said longitudinal bar and adjacent portions of said teeth, said cutter bars of the inner cutter terminating inwardly from the ends of said teeth in a shoulder extending substantially radially in said bore, and said inner cutter having a flat face extending longitudinally thereof from the base of said shoulder in spaced relation to the inner edges of said complementary bars and the ends of said teeth to provide a longitudinal channel between said cutter members.

4. A dry shaving head comprising an outer cutter member having a curved shaving section, a longitudinal bar forming the central portion of said section, a plurality of blunt cutting teeth projecting laterally in spaced parallel relation from one side of said longitudinal bar toward one side of said section, said side of said section having portions thereof projecting toward the ends of said teeth and terminating in spaced relation thereto, said projecting portions from said one side and said teeth having flat outer surfaces

lying in a plane extending in inclined relation to said side and intersecting said longitudinal bar, said longitudinal bar, teeth and said projecting portions having a continuous inner partially cylindrical surface, and an inner cutter member having a plurality of spaced parallel transverse cutter bars formed with a partially cylindrical outer surface engaging said inner partially cylindrical surface for cutting cooperation between said cutter bars and said teeth in reciprocation of one of said members relative to the other, said cutter bars terminating in spaced relation inwardly of the ends of said teeth and said inner cutter member having a longitudinal channel formed therein at the ends of said cutter bars to 15 space adjacent portions of said inner cutter member from the ends of said teeth and said projecting portions on said side.

5. A dry shaving head comprising an outer cutter member having a curved shaving section, a continuous longitudinal center portion forming part of said section, a plurality of spaced cutting members integral at opposite ends with said center portion and one side portion of said shaving

10 section respectively, a plurality of spaced parallel cutting teeth extending from the opposite side of said center portion toward the other side portion of said shaving section and having ends terminating in spaced relation to said other side portion of said shaving section, said teeth, cutting members and center portion having a partially cylindrical inner surface, and an inner cutter member having spaced cutter bars with the outer surfaces in partially cylindrical relation and engaging said partially cylindrical inner surface of said teeth, cutting members and center portion for cutting cooperation therewith in reciprocation thereof, said inner cutter member having the opposite ends of the cutter bars thereof terminating in shoulders intermediate the ends of said teeth and cutting members respectively, and said inner cutter member having longitudinal sections adjacent said shoulders in spaced relation inwardly of said cutting members and teeth to provide longitudinal channels between said inner and outer cutter members beyond the ends of the cutter bars of said inner cutter member.
